[57] CLAIM

The ornamental design for a towel rod, as shown and described.

DESCRIPTION

FIG. 1 is a perspective view of a towel rod showing my new design;

FIG. 2 is a front view thereof;

FIG. 3 is a rear view thereof;

FIG. 4 is a right side view thereof, the left side view being a mirror image of the right side;

FIG. 5 is a top plan view thereof; and,

FIG. 6 is a bottom plan view thereof.

The towel rod is shown broken-away in the views to indicate indeterminate length.

FIG. I
